UNITED STATES PATENT OFFICE.

DAVID S. WHITE, OF ST. PAUL, MINNESOTA, ASSIGNOR TO AMASA C. PAUL,
OF MINNEAPOLIS, MINNESOTA.

EXCAVATING-MACHINE.

SPECIFICATION forming part of Letters Patent No. 735,634, dated August 4, 1903.

Application filed September 28, 1900. Serial No. 31,864. (No model.)

To all whom it may concern:

Be it known that I, DAVID S. WHITE, of St. Paul, Ramsey county, Minnesota, have invented certain new and useful Improvements in Excavating-Machines, of which the following is a specification.

My invention relates to machines for hoisting material from sewer-ditches or other excavations; and the objects of the invention are, first, to provide means for rapidly handling sand, gravel, or other material that is taken from a sewer-ditch or other excavation; second, to provide a machine that can be quickly and conveniently moved from place to place along a sewer-ditch or from one excavation to another; third, to provide a machine that is light in weight, simple in construction, and therefore inexpensive to manufacture and easily operated.

The invention consists generally in various constructions and combinations, all as hereinafter described, and particularly pointed out in the claims.

In the accompanying drawings, forming part of this specification, Figure 1 is a side elevation of the machine, showing the hoisting-bucket in position to be lowered into the ditch or excavation. Fig. 2 is an end view showing the bucket raised and partially swung around to empty its contents into the hopper. Fig. 3 is a side elevation showing the bucket in position to dump its contents into the hopper. Figs. 4 and 5 are details in section of the mechanism whereon the rotating parts are supported. Fig. 6 is a sectional view on the line xx of Fig. 3. Fig. 7 is a detail of the stop device. Fig. 8 is a sectional view on the line yy of Fig. 1.

In the drawings, 2 2 represent the shoes or runners whereon the machine is supported, provided with clevises or bails 3 3 at each end, to which a team may be attached to draw the machine from place to place or along by the side of a sewer-ditch or other excavation.

4 4 are end cross-bars connecting the runners, and 5 5 are similar bars provided near the middle portion of the runners between upright braces 6 6.

7 7 are inclined standards provided on each runner, supporting the platform 8 and having suitable strengthening or bracing bars 9 9.

10 is an I-beam secured in an upright position to the bars 7 and the platform 8 at one side of the machine, and to the inner flanges of said beam a tube 11 is rigidly secured by 55 clamps 12. The lower end of said tube is threaded to fit within a flange 13, provided on a casing 14, that is closed on three sides and has suitable bearings for a rope or cable sheave 15. A hole 16 in the top of said 60 casing communicates with said tube. Beneath said casing is an upright stud 17, secured at its lower end to a block 18, provided between the top bars 5 and having collars 19 and 20, loosely mounted thereon, between 65 which, mounted on said stud, is a standard 21. The upper end of said stud and the collar 20 project through the bottom of said casing, and within said casing is a bracket 22, covering the top of said collar 20 and said 70 stud and preventing dust and dirt from entering between them. This construction permits the sheave-casing to be swung around on its bearing and allow the operator to attach the team to the cable on either side of 75 the machine. The sheave-casing being closed, except at one end, will prevent the cable or rope from becoming entangled with other parts of the mechanism and getting off the sheave and will also prevent dust and dirt 80 from entering the sheave and other bearings.

The standard 21 is adapted to turn in its bearings, and to its upper end bars 23 are rigidly secured, the upper end of said bars being connected with the tube 11 by a loose 85 collar connection 24, that permits the free rotation of the bars 23 about said tube. The upper ends of the bars 23 have horizontal extensions 25, between which a pulley 26 is mounted on a bolt 27, that passes through 90 short horizontal bars 28, provided, preferably, outside the parts 25. The outer ends of the bars 28 are upwardly turned for the purpose hereinafter described. The upright bars 23 are rigidly secured against vertical 95 movement, but are adapted to swing in a curved path and describe a partial revolution about the tube 11 in order that the material excavated may be elevated on one side of the machine and swung around and dumped on 100 the other side. Securely bolted to the bars 23, preferably near the platform 5, are short

bars 29, between which a channel-bar 30 is pivoted. This channel-bar forms the main boom or vertically-movable arm of the hoisting mechanism and may be of any preferred length and is preferably provided near its outer end with a short pivoted link 31, that is pivotally connected to a bar 32, that forms an auxiliary boom or continuation of the boom 30. The main and auxiliary booms are also preferably connected by the pivotal bar or link 33. Side bars 34 are also provided, having a common pivotal connection with the link 31 to the boom 32 and pivoted to the bars 28 near their turned-up ends. When the main hoisting-boom is raised to an upright position, as shown in Fig. 3, it enters the space between the ends of the bars 28 until it engages a forked stop 35, secured between the turned-up ends of the bars 28 and securely clamped to the side bars 34. At a suitable point near the outer end of the main boom 30 I provide a pulley 36 and a similar pulley 37 near the lower end of the auxiliary boom or bar 32. A suitable rope or cable 38 is attached to a bucket 39 and passes over said pulleys to the sheave 15 and from thence to a suitable source of power. When the bucket is being lowered into the ditch or other excavation, the main boom, with the other mechanisms connected therewith, will drop down from its normal upright position to a position overhanging the ditch to allow the bucket to be lowered into the excavation and filled. When the bucket is drawn up, the main boom will be raised to the position indicated by dotted lines in Fig. 1, and the operator standing on the platform may then swing the bucket and hoisting mechanism around to the opposite side of the machine in position for dumping.

As shown in Figs. 1 and 3, I prefer to cut away the flanges on the outside at the top of the I-beam 10 to permit the main boom to be swung around in proper position to dump the bucket. To receive the material as it is dumped from the bucket, I provide a hopper 40, pivotally supported on the arms or brackets 41 and normally locked in a horizontal position by the spring rod or bar 42. This bar is secured to the I-beam near its lower end and has a hook portion 43 near its upper end to overlap the edge of the hopper and prevent it from tilting. When, however, the operator desires to empty the hopper of its contents, a slight pull on the end of the spring-rod will disengage it from the hopper. I prefer also to provide a stop 44 to engage the edge of the hopper and prevent it from tilting in toward the machine.

The hoisting apparatus may be operated by one or more horses or other suitable power, and the mechanism for supporting the bucket being simple and quick-acting the bucket can be raised and emptied of its contents very rapidly. As soon as the hopper is filled it is dumped into a wagon or car standing beneath and carried to some other point along the

ditch or excavation. When the ditch or excavation has been carried down to the required depth, the machine is moved to another point in the manner heretofore described. The hoisting mechanism comprises but few parts, is easy of operation, and a single operator standing on the platform can readily swing the bucket and hoisting mechanism around to the proper dumping position over the hopper and then dump the filled hopper into the car or wagon beneath.

I am aware that various modifications, such as in the relative arrangements of the main and auxiliary boom and the pivotal parts connecting and supporting the same, will suggest themselves to any one skilled in the art, and I therefore do not wish to be confined to the details of the mechanism herein set forth.

Having thus described my invention, I claim as new and desire to secure by Letters Patent—

1. The combination, with a suitable frame, of an upright partially - rotating standard mounted therein, a suitable derrick device supported on said standard and adapted to swing therewith, said derrick device comprising a main and an auxiliary boom, suitable bars or links connecting said standard and said auxiliary boom, a suitable cable and bucket carried by said derrick device, and a hopper mounted on said frame and adapted to receive the material discharged from said bucket, substantially as described.

2. The combination, with a suitable frame, of an upright tube mounted thereon, a standard or mast pivotally supported in said frame and adapted to describe a partial revolution around said tube, a hoisting or derrick device supported on said standard and adapted to swing therewith, suitable sheaves provided on said standard and derrick device, and a rope or cable passing over said sheaves and through said tube to a suitable source of power, substantially as described.

3. The combination, with a suitable frame, of a fixed upright standard mounted thereon, a partially-rotatable standard supported on said fixed standard, a boom pivotally connected with said rotatable standard, an auxiliary boom, suitable bars or links pivotally connecting said main and said auxiliary booms, side bars or links pivotally connecting said auxiliary boom and said rotatable standard, suitable sheaves or pulleys provided on said standards and said booms, a hoisting-bucket and a suitable cable passing therefrom over said pulleys to a suitable source of power, substantially as described.

4. In a machine of the class described, the combination, with a fixed upright tube, of a stud provided beneath the same, a sheave-casing revolvably supported between said tube and said stud, a sheave mounted thereon, a suitable hoisting mechanism supported on said tube, and a rope or cable passing over said sheave through said tube to a suitable hoisting-bucket, substantially as described.

5. In a machine of the class described, the combination, with a frame, of a rotatable standard mounted therein, a main boom 30 pivotally supported on said standard, an auxiliary boom 32, bars or links pivotally connecting said booms, side bars pivotally connecting said auxiliary boom and said standard, a stop for limiting the upward movement of said main boom, sheaves provided on said standard and on said booms, a suitable hoisting-bucket, and a cable connected to said bucket and passing over said sheaves to a suitable source of power, substantially as described.
- 15 6. In a machine of the class described, the combination, with the tube 11, of a stud provided beneath said tube, a revolute sheave-casing provided between said stud and said tube, a revolute standard supported on said stud and said tube, a hoisting mechanism pivotally supported on said standard, suitable sheaves provided in said casing and on said standard and said hoisting mechanism, a suit-
- able hoisting-bucket and a cable connected to said bucket and passing over said sheaves 25 and through said tube to a suitable source of power, substantially as described.
7. The combination, with a suitable frame, of a hollow standard mounted therein, a partially-rotatable mast supported on said standard, a boom pivotally connected with said mast, an auxiliary boom, suitable means connecting said main and said auxiliary booms, means connecting said auxiliary boom to said mast, suitable sheaves or pulleys provided on 30 said boom, a hoisting-bucket and a suitable cable passing therefrom over said sheaves and through said hollow standard to a suitable source of power, substantially as described.
- 35 In witness whereof I have hereunto set my hand this 6th day of July, 1900.
- 40 DAVID S. WHITE.

In presence of--

A. C. PAUL,
M. C. NOONAN.
